(57) CLAIM

The ornamental design for a shorts having zipper along the front thigh as shown and described.

DESCRIPTION

FIG. 1 is a front elevational view of shorts with zipper along the front thigh;

FIG. 2 is a left side elevational view thereof;

FIG. 3 is a right side elevational view thereof;

FIG. 4 is a top view thereof;

FIG. 5 is a bottom view thereof;

FIG. 6 is a rear elevational view thereof;

FIG. 7 a perspective view thereof from the front left; and, FIG. 8 is a front elevational view thereof showing the zipper exposed.

The broken line showing the waistband and pleats in FIGS. 1-8 depict portions of the shorts with zipper along the front thigh which form no part of the claimed design.

The cross-hatching lines in the drawings show shading that defines the contours of the shorts with zipper along the front thigh and do not reflect a particular surface ornamentation or material.
